SLED

Harry L. Magun, New Haven, Conn.

Application October 10, 1945, Serial No. 621,543

12 Claims. (Cl. 280—21)

1

This invention relates to sleds or like articles, and more particularly to a device of this kind which may be called a ski-sled, in that it is normally supported in operation upon a single relatively broad runner which extends longitudinally of the body of the sled and substantially centrally of the body.

Means are provided, however, to steer the sled, and for this purpose two relatively short or steering runners are pivoted to the body of the sled, one adjacent each side edge, and near the front portion thereof, so that these runners are positioned adjacent each of the two front corners of the body.

A sled of this type may develop greater skill on the part of the operator in its handling, and will, therefore, be more attractive in some respects than the ordinary sled provided with two longitudinal side-edge runners. Moreover, according to the present invention the sled may be made very cheaply and economically, and at the same time be of durable construction so as to give good service.

One object of the invention is to provide a new and improved sled.

A further object of the invention is to provide a new and improved sled of the ski type, in that it is normally supported upon a single central longitudinally disposed runner.

Still another object of the invention is to provide a sled of the type described, with steering mechanism so that, while it will normally be supported upon a single relatively broad runner, it may be readily steered and kept in a desired path.

A still further object of the invention is to provide novel steering mechanism for a sled having a single centrally disposed longitudinally extending supporting runner.

To these and other ends the invention consists in the novel features and combinations of parts to be hereinafter described and claimed.

In the drawings:

Fig. 1 is a perspective view of a sled embodying my invention;

Fig. 2 is a top plan view of the front portion of the sled;

Figs. 3 and 4 are sectional views on lines 3—3 and 4—4 respectively, of Fig. 2;

Fig. 5 is a transverse sectional view on line 5—5 of Fig. 2;

Fig. 6 is a detail view of a part of the steering mechanism;

Fig. 7 is a top plan view of a modified form of my invention, in which the steering mechanism differs from that illustrated in Figs. 1 to 6;

Figs. 8 and 9 are enlarged sectional views on lines 8—8 and 9—9, respectively, of Fig. 7;

Fig. 10 is an enlarged front elevational view of the sled shown in Fig. 7; and

2

Fig. 11 is a view similar to Fig. 7, but showing the steering mechanism in another position.

To illustrate a preferred embodiment of my invention I have shown in Fig. 1 of the drawings a sled comprising a body portion 10 having secured thereto substantially centrally thereof and extending longitudinally thereof a relatively broad runner 11. As will be observed, this runner extends upwardly at the front and back of the sled, as shown at 12 and 13, and then extends laterally below the body 10, as shown at 14. In other words, this runner may be an endless strip of material having its upper side 14 secured to the body 10 of the sled, and its lower side 11 serving as the runner to form a single support for the body. While the runner 11 is shown as relatively broad as compared to the runner of the usual sled, its width, of course, may be varied depending upon the age and the skill of the user. This runner may also be provided with a groove 15 in its lower face, which will cause it to cling to the snow upon which it is moving and follow a relatively straight course.

Adjacent each of the forward corners of the body 10 of the sled is pivoted a steering runner. As shown in this figure of the drawing, these runners comprise a downwardly curved portion 16 adapted to contact the surface over which the sled is moving, which portions are curved upwardly adjacent the front of the sled and then rearwardly and substantially horizontally, as shown at 17, to a point adjacent the front of the body 10, where they are vertically offset, as shown at 18, and then extended rearwardly below the body, as shown at 19. These runners are pivoted to the body at 20, so that they may be free to swing and guide the sled in the desired path.

Adjacent the rear end of the portion 19 of each of the runners is pivoted at 21 one end of a strap 22, shown more especially in Fig. 6 of the drawings. This strap is provided with a central flat or horizontally disposed portion 23, at each side of which portion it is twisted to provide vertical portions 24 and again twisted to provide horizontal flat end portions 25 which are pivoted to the portion 19 of the steering runners. It will also be noted that the member 22 is inherently resilient so that it may be sprung in one direction or the other, particularly with respect to the vertically extending portions 24, and will tend to return to its original shape.

To the portion 23 of the strap 22 is secured the rear end of a lever 26 pivoted to the body of the sled at 28 and having secured at its front end at 29 the central portion of a steering bar or handle 30. This bar may be provided with hand grips 31 of rubber or the like, and the body 10 of the sled may also be provided with rubber grips 32 by which the sled may be held in the hands when in use.

It may be noted from Fig. 3 of the drawings, for example, that the steering runners 16 are not only considerably shorter than the supporting runner 11, but are also supported at a slightly higher level so that their lower surfaces are closer to the body of the sled than is the lower surface of the runner 11. Therefore, the runners 16, when the sled is being supported upon the runner 11, will be only lightly engaged, if engaged at all, with the surface over which the sled is traveling, so that the support of the sled with its passenger will be carried substantially entirely by the central runner 11. When it is desired to steer the sled, however, it may be tilted slightly to one side, thus causing the runner on that side to engage firmly with the surface of the snow. Each of these steering runners may be provided with a downwardly projecting V-shaped rib member 34 which extends longitudinally of the runner and which will cause it to grip the surface of the snow and properly steer the sled in the desired path. As shown, for example, in Figs. 3 and 4, the steering bar 30 will lie substantially upon the horizontal portion 17 of the runners 16, and will lie below the horizontal portion 14 of the supporting runner 11.

As will be obvious, when the handle bars are turned so as to swing the lever 27 about the pivot 28, the strap 22 will be flexed to cause the steering runners 15 to be turned in one direction or the other about the pivots 20. As the steering mechanism is pivoted to the body at three points, namely, 20, 21 and 28, it would be locked to the body were it not for the flexing of the strap 22. When the steering bar is released, the inherent resiliency of the strap will cause it to assume its normal position and thus bring the runners back to a neutral position, in which they will tend to remain until forced out of this position.

In Figs. 7 to 11 of the drawings I have shown a modified form of my invention which is substantially like that shown in Figs. 1 to 6 with the exception of the steering mechanism, so that this form of my invention comprises a sled body 10, an elongated central runner 11, and a steering runner 16 pivoted at each of the forward corners of the body. These steering runners are shaped substantially like those previously described, except that, as will be hereafter explained, the steering bars are secured to the runners. These bars may lie against the vertical portions 18 of these runners, and therefore these vertical portions are disposed slightly forwardly of the front edge of the body 10, as shown, for example, in Fig. 9.

The steering mechanism in this instance comprises a pair of steering bars 36, one rigidly secured upon the horizontal portion 17 of each of the steering runners 16, so that movement of these bars swings the steering runners about their pivots 20. A link 37 is pivoted at 38 to the upper horizontal portion 14 of the main runner forwardly of the sled body, and each end of this link is provided with a slot 39 to receive a pin 40 secured at the inner end of each of the bars 36, so that when the bars are moved about the pivots 20 the link 37 will also be moved about its pivot 38, thus causing the bars to move through equal angles. In order to bring about this effect, it will be noted that the slots 39 are slightly cam shaped so as to be curved rearwardly adjacent their inner ends. This will effect equal angular movements of the steering runners 16 in the same direction when either of the bars 36 is moved, as shown in Fig. 11.

In order that the steering bars may be resilient-

ly urged to a neutral position, a spring strap member 41 is secured by means of a bracket 42 to the upper portion 14 of the supporting runner, and the free ends of this strap extend laterally in each direction to engage the inner ends of the steering bars 36. As stated, this strap member 41 is resilient, and when the inner end of either bar is moved inwardly toward the body of the sled the corresponding end of the strap 41 will be sprung rearwardly, as shown in Fig. 11. When pressure upon the bar 36 is released, this end of the strap will tend to return to its normal position, thus bringing the steering mechanism back to a neutral position, which will usually be the position in which the runners would guide the sled in a straight path.

It will be observed that in both forms of my invention I have provided a sled in the nature of a ski-sled, in that it is supported upon a central runner and is provided adjacent its forward edge with two relatively short steering runners pivotally connected to the body of the sled. In addition, means in the form of handle bars or steering bars are provided for turning the steering runners about their pivots, and in each case there is resilient or spring means provided to normally hold these steering runners and the steering mechanism in a neutral position.

While I have shown and described some preferred embodiments of my invention, it will be understood that it is not to be limited to all of the details shown, but is capable of modification and variation within the spirit of the invention and within the scope of the claims.

35. What I claim is:

1. A sled having a flat body, a supporting runner extending longitudinally of the body and having upwardly and inwardly extending end portions secured to the body to rigidly secure the runner to the body in spaced relation thereto, said runner being positioned substantially midway between the side edges of the body, a pair of steering runners separately pivoted on vertical axes to the forward portion of the body one upon each side of said first runner, and steering means for moving said last-named runners about their pivots.

2. A sled having a flat body, a supporting runner extending longitudinally of the body and having upwardly and inwardly extending end portions secured to the body to rigidly secure the runner to the body in spaced relation thereto, said runner being positioned substantially midway between the side edges of the body, a pair of steering runners separately pivoted on vertical axes to the forward portion of the body one upon each side of said first runner, and steering means for moving said last-named runners about their pivots, said steering runners being substantially shorter than the supporting runner.

3. A sled having a flat body, a supporting runner extending longitudinally of the body and having upwardly and inwardly extending end portions secured to the body to rigidly secure the runner to the body in spaced relation thereto, said runner being positioned substantially midway between the side edges of the body, a pair of steering runners separately pivoted on vertical axes to the forward portion of the body one upon each side of said first runner, and steering means for moving said last-named runners about their pivots, said steering runners being substantially shorter than the supporting runner.

4. A sled having a flat body, a supporting runner extending longitudinally of the body and having upwardly and inwardly extending end portions secured to the body to rigidly secure the runner to the body in spaced relation thereto, said runner being positioned substantially midway between the side edges of the body, a pair of steering runners separately pivoted on vertical axes to the forward portion of the body one upon each side of said first runner, and steering means for moving said last-named runners about their pivots, the lower surfaces of said steering runners being closer to the sled body than the lower surface of the supporting runner.

4. A sled having a body, a supporting runner extending longitudinally of the body and rigidly secured in spaced relation thereto, said runner being positioned substantially midway between the side edges of the body, a pair of steering runners pivoted to the forward portion of the body one upon each side of said first runner, a steering bar pivotally secured to the body, and means connecting said bar to both said steering runners, said means including a flexible member rigidly connected with the bar and pivotally connected to the runners.

5. A sled having a body, a supporting runner extending longitudinally of the body and rigidly secured in spaced relation thereto, said runner being positioned substantially midway between the side edges of the body, a pair of steering runners pivoted to the forward portion of the body one upon each side of said first runner, steering mechanism comprising a lever pivoted to the body and extending longitudinally thereof, a steering bar secured to said lever forwardly of the body, and means connecting the rear end of the lever to said steering runners.

6. A sled having a body, a supporting runner extending longitudinally of the body and rigidly secured in spaced relation thereto, said runner being positioned substantially midway between the side edges of the body, a pair of steering runners pivoted to the forward portion of the body one upon each side of said first runner, steering mechanism comprising a lever pivoted to the body and extending longitudinally thereof, a steering bar secured to said lever forwardly of the body, and means connecting the rear end of the lever to said steering runners, said means comprising a resilient member pivoted to the steering runners and secured to said lever.

7. A sled having a body, a supporting runner extending longitudinally of the body and rigidly secured in spaced relation thereto, said runner being positioned substantially midway between the side edges of the body, a pair of steering runners pivoted to the forward portion of the body one upon each side of said first runner, and a steering bar movably connected with the body and operatively connected to the steering runners, said steering runners having horizontally disposed portions forwardly of and displaced downwardly from the sled body, and said bar being disposed above said portions.

8. A sled having a body, a supporting runner extending longitudinally of the body and rigidly secured in spaced relation thereto, said runner being positioned substantially midway between the side edges of the body, a pair of steering runners pivoted to the forward portion of the body one upon each side of said first runner, and steering means for moving said last-named runners about their pivots, said means comprising a link pivoted to the main runner forwardly of the body portion, a steering bar secured to each of said steering runners, and means operatively connecting the adjacent ends of said steering bars to said link.

9. A sled having a body, a supporting runner extending longitudinally of the body and rigidly secured in spaced relation thereto, said runner being positioned substantially midway between the side edges of the body, a pair of steering runners pivoted to the forward portion of the body one upon each side of said first runner, and steering means for moving said last-named runners about their pivots, said means comprising a link

pivoted to the main runner forwardly of the body portion, a steering bar secured to each of said steering runners, and means operatively connecting the adjacent ends of said steering bars to said link, said means comprising a pin in one of said members and a pin-receiving slot in the other of said members.

10. A sled having a body, a supporting runner extending longitudinally of the body and rigidly secured in spaced relation thereto, said runner being positioned substantially midway between the side edges of the body, a pair of steering runners pivoted to the forward portion of the body one upon each side of said first runner, and steering means for moving said last-named runners about their pivots, said means comprising a link pivoted to the main runner forwardly of the body portion, a steering bar secured to each of said steering runners, and means operatively connecting the adjacent ends of said steering bars to said link, said means providing a pin in one of said members and a pin-receiving slot in the other of said members, and said slots being cam shaped to effect equal movement of said bars and steering runners.

11. A sled having a body, a supporting runner extending longitudinally of the body and rigidly secured in spaced relation thereto, said runner being positioned substantially midway between the side edges of the body, a pair of steering runners pivoted to the forward portion of the body one upon each side of said first runner, and steering means for moving said last-named runners about their pivots, said means comprising a link pivoted to the main runner forwardly of the body portion, a steering bar secured to each of said steering runners, means operatively connecting the adjacent ends of said steering bars to said link, and resilient means normally urging said steering runners to a neutral position.

12. A sled having a body, a supporting runner extending longitudinally of the body and rigidly secured in spaced relation thereto, said runner being positioned substantially midway between the side edges of the body, a pair of steering runners pivoted to the forward portion of the body one upon each side of said first runner, and steering means for moving said last-named runners about their pivots, said means comprising a link pivoted to the main runner forwardly of the body portion, a steering bar secured to each of said steering runners, means operatively connecting the adjacent ends of said steering bars to said link, and resilient means normally urging said steering runners to a neutral position, said means comprising a spring strap member fixed at its central portion with relation to the body of the sled and having free ends engaging said steering bars.
